UNITED STATES PATENT OFFICE.

CHARLES HARCOURT WHITE, OF NEW YORK, N. Y.

LATCH-LOCK FOR CAR-DOORS.

SPECIFICATION forming part of Letters Patent No. 352,213, dated November 9, 1886.

Application filed September 22, 1886. Serial No. 214,246. (Model.)

To all whom it may concern:

Be it known that I, CHARLES HARCOURT WHITE, of the city and county of New York, in the State of New York, have invented a new and useful Improvement in Latch-Locks for Car-Doors, of which the following is a specification.

In my United States Letters Patent No. 325,371, granted September 1, 1885, I have shown and described a latch for car-doors and other sliding doors, which comprises a tongue supported by a horizontal pivot, so as to swing in a vertical plane to engage with and disengage from a hook upon the door-casing, handles whereby the door may be moved, and which have a slight swinging movement, and a draw-bar which forms a connection between the handles and the pivoted tongue, and through which the pivoted tongue may be raised or lifted, so as to disengage it from the hook upon the casing.

The object of my present invention is to provide, in connection with a latch of the kind above described, a lock whereby the pivoted tongue may be locked against rising, and thereby held securely in engagement with the hook upon the door-casing.

According to my invention I prefer to perform the locking of the pivoted tongue, to prevent its rising, by means of a locking-bolt engaging with the draw-bar; but the locking of the tongue may be effected in other ways. With a latch of the kind above described I also employ handle-plates applied to opposite faces of the door, and according to my present invention I make one of these handle-plates hollow, so that it constitutes a casing, within which the draw-bar is arranged, and within which is also arranged a lock for holding the pivoted tongue down or against being lifted.

The invention consists in novel combinations of parts, which are hereinafter described, and pointed out in the claims.

In the accompanying drawings, Figure 1 is a sectional view of a latch-lock embodying my invention, upon the plane of the dotted line xx , Fig. 3. Fig. 2 is a face view of my latch-lock, showing its position when applied to a door. Fig. 3 is a sectional view upon the plane of the dotted line yy , Fig. 1; and Fig. 4 is a hori-

zontal section upon the plane of the dotted line zz , Fig. 1.

Similar letters of reference designate corresponding parts in all the figures.

A designates a portion of a door, having applied to its opposite sides handle-plates B B', which are secured by screws b thereto, and in these handle-plates are journaled two handles, C C', at opposite sides of the door, which are connected with each other by a spindle portion, C². In the edge portion of the door is formed a notch, s, wherein is secured a tongue-case, D, similar in construction to that shown in my aforesaid Letters Patent, and within which is arranged a tongue, E, which is mounted upon a horizontal pivot, e, so that it may swing in a vertical plane, and which by so swinging in a vertical plane is made to engage with or to disengage itself from a hook, f, projecting from a plate, F, which is to be secured to the casing of the door. The door is held closed by the pivoted tongue E engaging the hook f.

G designates a draw-bar which has at one end a pin or stud, h, projecting through an arc-shaped slot, h', into the tongue-case D and engaging the pivoted tongue, and near the other end of this draw-bar is a socket or perforation, h², which receives a stud or projection, h³, projecting inward from the handle C', and formed integral therewith. The stud or projection h³ works through an arc-shaped slot, h⁴, in the handle-plate B', as shown in Fig. 2.

From this description it will be understood that when the handle C is moved in the direction indicated by the arrow in Fig. 2 the draw-bar G will be moved in the direction indicated by the arrow thereon in Fig. 1, and will thereby lift the pivoted tongue E out of engagement with the hook f.

I have in Fig. 1 represented a spring, h⁵, as bearing against the end of the draw-bar G, and when the handle is released this spring will throw the draw-bar and handle in the opposite direction to that indicated by the arrow in Fig. 2, and will throw down the tongue, the movement of the tongue being limited by the stud h or h³ striking the end of the slot h' or h⁴.

In so far as described the latch does not differ substantially from that shown in my afore-

said patent; but I combine with the latch a lock, whereby the pivoted tongue E may be held against movement and permanently engaged with the hook f whenever desired. I 5 prefer to effect this locking of the pivoted tongue E by means applied to the draw-bar G, as the tongue cannot lift without a corresponding inward movement being imparted to the draw-bar G.

10 In this example of my invention the handle-plate B' is hollow, or consists of a shell closed upon the inner side, which comes next the door, by a false plate, B², and affording space within it for the arrangement of the draw-bar 15 G and the spring h⁵.

H designates a locking-bolt, which is guided by a pin or stud, i, engaging a slot, i', therein, and which is furthermore guided by projections or posts i², cast within the hollow handle-plate B'. The sliding bolt H carries a projection, j, which may engage with the projection j' upon the draw-bar G, and said bolt has a notch, j², with which may be engaged a key inserted through the key-hole j³.

25 In connection with the locking-bolt H, I employ a tumbler, I, which lies parallel with and at the side of the bolt H, and is supported upon the pin i, and also by a projection, k, extending across and resting upon the top of the bolt 30 H. Upon the top of the bolt H is a projection or horn, k', on either side of which the projection k of the tumbler I may lie, according to whether the bolt H is moved in one direction or the other. The tumbler I has applied to it a spring, k², which exerts a constant 35 tendency to maintain the projection k in engagement with the projection k'.

In Fig. 1 I have represented the locking-bolt H as in its locking position, in which its 40 projection j engages the projection j' upon the draw-bar G, and thus prevents the lifting of the pivoted tongue E. If it be desired to unlock the draw-bar, the key inserted through the key-hole j³ is turned and comes into the 45 notch j² in the bolt H. The turning of the key lifts the tumbler I so as to carry its projection k above the path of the projection k'

upon the bolt I, and the further turning of the key, by acting in the notch j² of the bolt H, moves said bolt toward the left of Fig. 1, and 50 retracts the projection j away from the projection j' on the draw-bar G. As the turning of the key is completed the tumbler is thrown downward and its projection k comes upon the opposite side of the projection k' to that represented in Fig. 1, thereby holding the bolt 55 against movement toward the right.

From the above description it will be seen that by a very simple construction and combination of parts I provide a latch-lock of 60 great strength and simplicity, and although it is specially intended for car-doors, it may be employed for sliding doors in other structures.

What I claim as my invention, and desire to secure by Letters Patent, is— 65

1. The combination, with the horizontally-pivoted tongue and handles of a car-door latch, and a draw-bar connecting the handles with the tongue for lifting the latter, of a lock whereby the tongue may be held against lifting, substantially as herein described. 70

2. The combination, with the horizontally-pivoted tongue and handles of a car-door latch, and a draw-bar connecting the handles with the tongue for lifting the tongue, of a hollow 75 handle-plate to be applied to the face of the door and in which said draw-bar works, and a lock also arranged in said hollow handle-plate, whereby the tongue may be held against rising, substantially as herein described. 80

3. The combination, with the horizontally-pivoted tongue and handles of a car-door latch, of the draw-bar G, connecting the handles and tongue and provided with the upward projection j', the sliding locking-bolt H, having the 85 projection j for engaging the inner side of the projection of the draw-bar when moved to a locking position, and the pivoted tumbler I, applied to said bolt, substantially as herein described.

CHARLES HARCOURT WHITE.
